UNITED STATES PATENT OFFICE.

JOHN MEHL, JR., OF JERSEY CITY, NEW JERSEY.

DESIGN FOR A BUCKLE.

SPECIFICATION forming part of Design No. 28,967, dated April 27, 1897.

Application filed March 12, 1897. Serial No. 627,248. Term of patent 3½ years.

To all whom it may concern:

Be it known that I, JOHN MEHL, Jr., a citizen of the United States, residing at Jersey City, in the county of Hudson and State of New Jersey, have invented and produced a new and original Design for a Belt-Buckle, of which the following is a specification, reference being had to the accompanying drawings, forming a part thereof, in which—

5 Figure 1 is a plan view of a buckle embodying the features of my design. Fig. 2 is an edge view of the buckle; and Fig. 3 is a section through a member of the body of the buckle, taken on the line 3 3 of Fig. 1.

15 The leading feature of the design is in the formation of the body of the buckle consisting of side members A and a front member B. The rear ends of the side members are given a downward curve, as shown at a in Fig.

2, and, as shown in Fig. 3 in cross-section, 20 each member is arched from its inner edge to a point near its outer edge, the outer edge portion a' being approximately straight. Another feature of the design consists in leaving the arched portion of the body plain and forming beads b upon the straight portion a'. A bar d apparently connects the rear ends of the side pieces of the buckle, and a tongue D is supported upon the bar, the free end of the tongue having an upward curve, as shown in 30 Fig. 2.

I claim—

The design for the buckle herein shown and described.
